UNITED STATES PATENT OFFICE.

GUSTAVE FERNEKES, OF WEST ELIZABETH, PENNSYLVANIA, ASSIGNOR TO JOHN A. SNEE, OF WEST ELIZABETH, PENNSYLVANIA.

METHOD OF PRODUCING FORMALDEHYDE.

1,038,547.

Specification of Letters Patent. Patented Sept. 17, 1912.

Continuation of application Serial No. 609,441, filed February 18, 1911. This application filed May 11, 1912. Serial No. 696,711.

To all whom it may concern:

Be it known that I, GUSTAVE FERNEKES, a resident of West Elizabeth, in the county of Allegheny and State of Pennsylvania, have 5 invented certain new and useful Improvements in Methods of Producing Formaldehyde, of which the following is a specification.

The invention of this application (a continuation of my application filed February 18, 1911, Serial No. 609,441) relates to the production of formaldehyde by the oxidation of a stream or column of air and methane mixed in proper proportions, or 10 a portion of such stream or column, without employing either catalyzing or absorbing agents. The formaldehyde-producing stream is enveloped to exclude outside air and is heated sufficiently to cause the necessary oxidation, such oxidation being arrested before it proceeds beyond the formaldehyde-forming stage. The formaldehyde and other substances resulting from such incomplete oxidation may be separated by a 15 process of absorption or in any other suitable manner.

The producing stream of mixed air and gas may be variously enveloped to exclude the outer air and to attain the requisite temperature. The mode herein disclosed utilizes the outer portion of the stream or column as an envelop for the inner formaldehyde-producing portion thereof, such outer portion being a flame and generating the necessary oxidizing heat for the cooler inner portion and at the same time excluding the outer air from the latter which if admitted would cause excessive oxidation and conversion of the entire stream or column into carbon dioxide, water, formic acid, etc., and there would be no appreciable yield of formaldehyde. A Bunsen burner or other air and gas mixing means which will discharge a stream of mixed air and gas into a circumscribed flame space is well suited for the purpose, with means for baffling the inner formaldehyde-producing portion of the stream before oxidation thereof proceeds too far, and with means for cooling and for 20 removing the formaldehyde from the flame space.

It is known that the flame-enclosed area of a burning stream or column of mixed air and gas issuing from a Bunsen burner or

other source consists of at least three zones 55 which extend outwardly for a distance from such source, all of which zones merge or disappear at the normal extremity of the flame or inwardly from such point. In that portion of the flame length in which the three 60 zones are defined there is an outside flame-composed zone, an intermediate zone of reduced temperature, and finally a central zone of relatively cool mixed air and gas which has not attained ignition temperature. 65 But the heat from the burning outer zone is sufficient to oxidize the substances of the inner zone to formaldehyde, and at the same time the flame zone excludes the outer air from the inner zone and excessive oxidation 70 of the latter is prevented. It is necessary to baffle, check, or cool the entire zone-comprised column or stream before oxidation can proceed beyond the formaldehyde-producing point, otherwise substantially complete oxidation would result and the purpose of the invention would be defeated.

In the accompanying drawings, I have illustrated a form of apparatus for practising the invention, Figure 1 being a vertical 80 section of the combustion chamber and its inclosing jacket, and Fig. 2 a sectional plan on line 2-2 of Fig. 1.

Referring to the drawings, the combustion chamber is preferably formed with a solid 85 or imperforate bottom 2, and a closed top 3 of metal or other refractory material. The chamber here shown is circular with its side wall 4 formed of an open screen or gauze which is reinforced by a skeleton frame 5, 90 wire mesh, such as copper or other metal being well suited for the purpose. Mixed air and gas are entered in the combustion chamber, preferably through bottom 2 thereof, by any suitable means. Such admission may be 95 efficiently accomplished by means of a Bunsen burner 6 provided with an air inlet at the exterior of the chamber, the burner being equipped with a suitable regulating valve 7.

8 is the gas inlet pipe, and 9 the valve 100 controlling the gas supply. The burner and valves 7 and 9 are of usual and well known construction.

The combustion chamber is incased in a jacket 10 provided with air inlets 11, the latter being preferably in the plane of the lower portion of the chamber. Pipe 13 extends from the jacket hood 12 for conduct-

ing the formaldehyde and other substances to absorption apparatus or other means for separating them, well known in the art.

The flaming stream or column of mixed air and gas is projected against top plate 3 before it attains its full length and before the zones hereinbefore referred to merge or disappear, with the result that the entire stream or column is cooled before excessive oxidation can occur. The exposed top surface of plate 3 maintains it relatively cool, and if desired it may be cooled artificially by any suitable means, also it may be formed of material that is a ready conductor and radiator of heat the effect of which will be to minimize its temperature. In addition to cooling the column or stream, plate 3 deflects the formaldehyde and other substances laterally through screen 4, which still further cools them and removes them from the flame space or area and prevents burning or flashing.

I claim.

1. The method of producing formaldehyde consisting in heating a stream containing air and methane to formaldehyde-producing temperature with the outer air excluded from the inner part of the stream, and baffling the stream with a heat conducting medium.

2. The method of producing formaldehyde consisting in heating a stream containing air and methane to formaldehyde-producing temperature, and baffling and cooling the stream before oxidation thereof proceeds beyond the formaldehyde-producing stage.

3. The method of producing formaldehyde consisting in producing a stream containing air and methane with the stream consisting of an inner part and an outer part and with the outer part forming an envelop for the inner part and excluding outer air therefrom, heating the outer part of the stream to ignition temperature and thereby oxidizing the inner part thereof to formaldehyde and cooling both portions of the stream before oxidation of the inner portion thereof

can proceed beyond the formaldehyde-producing stage.

4. The method of producing formaldehyde 50 consisting in baffling flaming air and methane with a heat conducting medium before they are fully consumed, and removing the unconsumed substances from the flame.

5. The method of producing formaldehyde 55 consisting in burning air and methane in a flame-confining space, baffling the flaming air and methane before they are fully oxidized, and removing the unconsumed substances from the flame-confining space. 60

6. The method of producing formaldehyde consisting in sustaining a flame by a stream containing air and methane with the exterior of the flame area—inwardly from the flame extremity—of higher temperature 65 than its interior, baffling the stream before the air and methane of the inner portion of the stream are fully oxidized, and removing the unconsumed substances from the flame. 70

7. The method of producing formaldehyde consisting in baffling a flaming stream containing air and methane before they are fully consumed, oxidizing to formaldehyde the formaldehyde-producing portion of the 75 stream, and removing the formaldehyde and other unconsumed substances from the flame.

8. The method of producing formaldehyde consisting in baffling a flaming stream containing air and methane before the substances are fully consumed with a portion of the stream relatively cool when baffled, oxidizing to formaldehyde the relatively cool portion of the stream, and removing 85 the formaldehyde and other unconsumed substances from the flame.

In testimony whereof I affix my signature in presence of two witnesses.

GUSTAVE FERNEKES.
